ABRADING DEVICE

James Luther Culpepper, Pearl Harbor, Territory
of Hawaii

Application August 22, 1940, Serial No. 353,724

3 Claims. (Cl. 51—197)

This invention relates to a novel abrading device and more particularly to a sanding machine adapted to be used as an attachment to a drill press.

More particularly it is an aim of the invention to provide an abrading device including a plurality of abrading disks mounted to turn freely relatively to a rotatable cross head and adapted to be rotated by frictional engagement with the surface to be treated in a direction opposite to the rotation of the cross head for uniformly scraping the surface to be treated.

In abrading devices employing a driven rotary abrading disk, a portion of the surface adjacent the axis of the disk is not scraped as much as the portion adjacent the periphery and as a result it is difficult to secure a uniformly abraded surface. In the present invention, the planetary action resulting from the rotation of the disks around a stock or shaft and the rotation of the individual disks relatively to the cross head results in a substantially uniform treatment of the surface being scraped.

Still another aim of the invention is to provide means whereby abrading members may be individually adjusted relatively to the cross head for adjustably positioning them relatively to one another and means for yieldably mounting the cross head relatively to the stock or shaft to permit a rocking movement of the cross head so that the abrading members may adapt themselves to uneven portions in the surface being treated.

Other objects and advantages of the invention will hereinafter become more fully apparent from the following description of the drawings, which illustrate a preferred embodiment thereof, and wherein:

Figure 1 is a top plan view of the abrading device,

Figure 2 is a side elevational view of the same.
Figure 3 is a longitudinal vertical sectional view taken substantially along the plane of the line 3—3 of Figure 1.

Figure 4 is a transverse vertical sectional view taken substantially along the plane of the line 4—4 of Figure 1.

Figure 5 is a horizontal sectional view taken substantially along the plane of the line 5—5 of Figure 2.

Figure 6 is a fragmentary side elevational view partly in section, showing a slightly modified form of the invention, and

Figure 7 is a perspective view of the abrading element shown detached from the device.

Referring more particularly to the drawings,

wherein like reference characters designate like or corresponding parts throughout the different views, 10 designates generally the abrading or sanding machine including a stock or shaft 11 which is adapted to be secured at its upper end 5 in the chuck of a drill press, not shown, in a conventional manner. The stock 11 is provided with a restricted opposite end 12 in the upper portion of which is mounted a collar 13. The free end of the restricted portion 12 is secured 10 in one end of a universal joint 14 in any suitable manner, not shown, which end serves to retain the collar 13 in position on the stock 11, as best illustrated in Figure 3. A cross head 15 is provided with a recess 16, intermediate of its ends, 15 to receive the opposite end 17 of the universal joint 14 which is detachably secured thereto by means of a set screw 18. An expansion coil spring 19 is disposed between the collar 13 and the upper side of the cross head 15. As best seen 20 in Figure 3, the upper coil of the spring 19 engages around the lower portion of the periphery of the collar 13 and against the under side of an annular flange 20 which extends outwardly from the upper portion of the periphery of the collar. 25

The cross head 15, adjacent each of its ends, is provided with a perpendicular bore 21, in which is rotatably mounted a portion of the shank of a headed pin 22. An angular lubricating bore 23 communicates with each of the bores 21. Each of the bores 23 is provided with an internally threaded open end 24, which opens outwardly of the upper side of the cross head 15. The opposite ends of the bores 23 are sealed at 25. The bores 23 are adapted to be filled with a lubricant 35 not shown, for lubricating the bores 21 and the portions of the pins 22 disposed therein and their ends 24 are adapted to be normally closed by means of headed screws 26. It will be noted that the bores 23 extend downwardly and outwardly 40 relatively to the end portions of the cross head 15 so that the lubricant contained therein will be directed toward the bores 21 by centrifugal force when the device is in operation.

A disk shaped abrading member 27 is adapted 45 to be connected to each of the pins 22. Each of the abrading members 27 includes a disk portion 28 which is provided with an upset peripheral flange 29 the ends of which terminate in spaced apart relationship to one another to form a gap 50 30. The abrading members 27 are each provided with an upset centrally disposed enlargement 31 having an upwardly opening centrally disposed recess 32 for receiving the lower portion of the shank of one of the pins 22. The por- 55

tions 31, as best seen in Figure 5, are provided with set screws 33 which extend into the recesses 32 for engaging the pins 22 for securing the members 27 thereto. It will be noted that the 5 set screws 32 are aligned with the gaps 30 so that the blade of a screw driver, for example, not shown, may be disposed in the gaps for tightening or loosening said set screws. As best seen in Figure 3, the shank ends of the pins 22 do not 10 extend to the bottoms of the recesses 32 so that the abrading members 27 may be raised to compensate for wear on the under side of the heads of the pins 22, on the washers 34, on cross head 15, and on the portions 31 to thereby prevent the 15 disks 27 from rocking relatively to the cross head 15. Washers or anti-friction members 34 are preferably disposed between the cross head 15 and the headed ends of the pins 22 and the enlargements 31 to prevent wear on the cross 20 head, pins and enlargements.

As best seen in Figure 7, a cup shaped abrading member 35 is shaped and sized to fit over the outer side of each of the members 27 and is provided with a flange 36 for engaging the outer side 25 of the flange 29. The flange 36 is provided with a gap 37 to register with the gap 30. A spring clip 38 is yieldably disposed around the outer side of the flange 36 of each of the abrading elements 35 and is provided with a hooked end 39 for engaging around corresponding ends of the flanges 29 and 36, as best seen in Figure 5, and an in-turned opposite end 40 for engaging over the opposite ends of the flanges 29 and 36. The 30 spring clip 38 is adapted to resiliently clamp the flange 36 to the outer side of the flange 29 to provide means whereby an abrading element 35 may be detachably mounted on each of the abrading members 27. The terminals in the ends 40 of the clips 38 extend inwardly to provide handle 45 portions by means of which the clips may be attached to or detached from the members 27. The outer sides of the disk portions 28 and the flanges 29 are adapted to be serrated or roughened, not shown, for frictionally engaging the 50 inner sides of the abrading elements 35 to prevent said elements from moving relatively to the members 27 when attached thereto by the clips 38. The abrading elements 35 may be provided with a coating of any one of a number of abrading materials, such as sand or emery. As best 55 seen in Figure 3, the outer side of the disk 28, where it joins the flange 29, is rounded to prevent element 35 wearing through between its bottom and flange 36.

55 From the foregoing it will be obvious that when the stock 11 is attached to the chuck of a drill press and is rotated thereby, it will rotate the cross head 15 to cause the abrading members 27 to revolve around the stock 11. Assuming 60 that the stock and cross head are turning in a clockwise direction, as illustrated in Figure 1, when the abrading elements 35 of the abrading members 27 are brought into contact with the surface to be treated, not shown, frictional contact therewith will cause the members 27 to revolve on the pins 22 in a counter-clockwise direction, or in the opposite direction to which they are revolving around the stock 11. As a 65 result, the portion of the surface being treated which is substantially beneath the stock 11 will be scraped by the members 27 turning relatively to said portion in the direction opposite to the direction in which the cross head is revolving while the remote portions of the members 27 will

revolve to a certain extent by contact with the outer portion of the part of the surface being treated so that said portion cannot be scraped as much by each individual part of the disk to thereby substantially equalize the scraping or polishing of the surface. In other words, the portions of the abrading members which are disposed between the pins 22 will be turning against the surface being treated while the portions beyond the pins will be turning with the surface. 10 The expansion coil spring 19 permits the cross head to rock relatively to the stock 11 on its universal joint 14 so that the abrading members 27 may adjust themselves to portions of the surface which are not level and also prevents the 15 cross head 15 from rocking sufficiently so that the abrading elements 35 will be moved out of contact with the surface which would occur if the cross head is moved from its normal position through an arc in excess of 45 degrees. For some 20 operations, such as paralleling wood, it is necessary that the cross head 15 be rigidly disposed relatively to the stock or shaft 11. When the device 10 is used for such work, a rigid sleeve 41 replaces the spring 19 for holding the cross head 25 15 rigid relatively to the stock 11. These parts may be interchanged readily by merely loosening the set screw 18 and detach the cross head 15.

Various modifications and changes are contemplated and may obviously be resorted to as 30 only a preferred embodiment of the invention has been disclosed.

I claim as my invention:

1. A surfacing device comprising a stock adapted to be connected to the chuck of a drill press 35 to be rotated thereby, a cross head, a universal joint connecting said cross head and stock, abrading members disposed beneath and rotatably connected to the cross head for engaging a surface to be treated, a collar on the stock above the 40 universal joint, and an expansion coil spring mounted between the collar and crosshead and surrounding the universal joint.

2. An abrading machine comprising a rotating shaft, a cross head secured to one end of said 45 shaft, abrading members connected to said cross head and having their working surfaces disposed substantially in the same plane for engaging the surface to be treated, said abrading members being mounted to rotate freely relatively to the 50 cross head whereby said members will be rotated in opposite directions to the cross head and shaft through frictional engagement with the surface to be treated, a universal joint for connecting the crosshead, intermediate of its 55 ends, to said shaft, and yieldable means for normally retaining the crosshead substantially at a right angle to the shaft, and for limiting its rocking movement relatively to the shaft, said yieldable means including a collar secured to the 60 stock above the universal joint, and an expansion coil spring mounted between the collar and crosshead and surrounding the universal joint.

3. In a surfacing device, an abrading member comprising a disk having an upset peripheral 65 flange, said flange being provided with a gap, an abrading element constructed and arranged to receive said disk, and a spring clip having end portions detachably connected to the ends of the flange, formed by the gap, said clip engaging 70 around the flange portion of the abrading member for yieldably clamping it to the flange portion of the disk.

JAMES L. CULPEPPER.
